UNITED STATES PATENT OFFICE.

JAY A. MACKEY, OF LYNN, MASSACHUSETTS, ASSIGNOR TO HAMEL SHOE MACHINERY COMPANY, OF LYNN, MASSACHUSETTS, A CORPORATION OF MASSACHUSETTS.

WELT GROOVING AND BEVELING MACHINE.

1,286,696.

Specification of Letters Patent.

Patented Dec. 3, 1918.

Application filed March 6, 1917. Serial No. 152,881.

To all whom it may concern:

Be it known that I, JAY A. MACKEY, a citizen of the United States, and resident of Lynn, county of Essex, Commonwealth of Massachusetts, have invented an Improvement in Welt Grooving and Beveling Machines, of which the following description, in connection with the accompanying drawings, is a specification, like characters on the 10 drawings representing like parts in each of the several views.

This invention relates to mechanism for operating on welt strips such as used for example in the Goodyear welt system of 15 shoe manufacture to produce a groove therein for the stitching line and also to bevel the edge thereof. One prime object of the invention is to provide improved means for producing rapidly and accurately a continuous groove in one side of the welt, such means having provision for assuring a perfectly uniform sewing thickness from the bottom of such groove to the other side of the welt regardless of variations in the thickness of the welt strip. In carrying out this 20 feature of the invention I preferably provide a grooving knife held in rigid and unyielding adjustment with no springs or like resilient elements in the mounting, and also 25 provide accurate guiding means for the welt strip adapted to hold it in precise alinement and correct operative relation with the grooving knife as it passes through the machine. A further object is to provide improved means 30 for effecting a quick adjustment of the feed roll for the welt strip. A still further object is to provide improved means for adjusting the grooving knife holder, this including preferably a turning stud as a part 35 of the knife mounting whereby as the knife is ground it can be kept to center at all times. A still further object is to provide an improved mounting and adjustment of the bevel knife holder adapted to insure an accurate and uniform bevel of the desired 45 character. The foregoing and other objects and advantages of the invention will more fully appear from the following detailed description, and the distinctive features of 50 novelty will be pointed out in the appended claims.

Referring to the drawings:

Figure 1 is a side elevation of a machine embodying the features of my invention,

with a portion of the driving connection 55 broken away;

Fig. 2 is a plan view of the machine with a feed roll and the head bearing the grooving knife broken away;

Fig. 3 is a side elevation looking from the 60 right in Fig. 1;

Fig. 4 is a detail showing the grooving knife and its mounting removed; and

Fig. 5 is a detail showing the mounting 65 of the beveling knife.

The operative elements of the machine are mounted on a suitable base or pedestal 1 having an upright post 2 constituting a support for the feed wheel 3. This feed wheel which is formed with ratchet feed teeth 4 70 is fixed at the inner end of a shaft 5 suitably driven, preferably by a pulley (not shown) at the outer end thereof. This shaft is fitted in a bearing sleeve 6 having a depending shank 7 fitted for vertical sliding 75 adjustment in the upright 2, such adjustment being preferably effected by a turn buckle 8 having reversely threaded projections 9, 10 fitted in the shank 7 and in the upright 2 respectively. For clamping the 80 feed wheel mounting, rigidly and securely in position as thus adjusted, a clamping screw 11 may be fitted transversely into the upright 2 to engage the shank 7, this screw having as shown a squared projecting end 85 to be engaged by a wrench or like operating tool. The upright 2 also constitutes a mounting for an idler roll 12 mounted opposite the feed roll 3, the upright having for this purpose a laterally extending bearing 90 boss 13 to which the roll 12 is fitted as by a pivot stud 14. At the top of the upright 2 a block 15 is fitted for adjustment lengthwise of the feed wheel face, having for this purpose a shank 16 slidably fitted in the top 95 of the upright 2 and adapted to be clamped in adjusted position by a set screw 17. The block 15 is of considerable width as best seen in Fig. 2, having a portion 15^a that projects laterally underneath the feed wheel 3, this block intersecting the lower portion of the feed wheel and being recessed as seen at 18 to afford clearance for the feed wheel which extends down into a recess 19 extending transversely across the forward portion 100 of the block 15 and constituting a feed and guide passage for the welt strip under operation. The lower portion of the block 15

is also recessed to afford clearance for the roll 12, which is mounted so that the top thereof is flush with the bottom of the guide passage 19 as seen at 20. It will thus be observed that the feed wheel 3 may be adjusted by means of the turn buckle 8 so as to extend downward a greater or less distance into the guide passage 19 to space it accurately from the bottom of the passage 19 and the idler roll 12 according to the thickness of the welt strip being treated.

At the other side of the base 1 from the upright 2 is another upright 21 constituting a support and mounting for the grooving and beveling knives. At the top of the upright 21 a block 22 is mounted for adjustment toward and from the welt passage and is clamped in adjusted position by a clamp screw 23 fitted into the upright 21 and passing through an elongated slot 24 of said block; this block 22 as well as the shank 16 of the block 15 being fitted in ways of the respective uprights to insure right line adjusting movement. The inner end of the block 22 extends into an intermediate portion of the block 15 which is recessed to provide adjusting clearance therefor and the inner end of the block 22 constitutes the outer side wall of the guide passage 19 as indicated at 22^a. At the inner end portion of this block 22 is mounted a beveling knife 25, this being diagonally fitted in a knife holder 26 adjustably clamped to the block 22 by means of a clamp bolt 27 passing through an elongated slot 28 in the block. The inner operating end of the beveling knife 25 thus projects diagonally from the lower corner of the end 22^a of the block 22 and is held rigid and secure in its adjusted position by said block and its auxiliary clamping block 26 whereby accuracy and uniformity in the bevel cut is insured; it being particularly noted that the block 22 which thus constitutes a support and backing for the beveling knife is of substantial dimension and held in its seat in the top of the upright 21 in a manner to preclude any possibility of chattering or looseness. For mounting the grooving knife the upright 21 has a further upward extension 29 equipped with a vertical slide way 30 in which is fitted an upwardly extending shank 31 of a bearing sleeve 32 in which is fitted a stud mounting 33 for the grooving knife. The bearing sleeve 32 is vertically adjustable by means of an adjusting screw 34 threaded into the shank 31 thereof and swiveled at 35 in the top of the extension 29, this screw having a suitable knurled operating head 36. For clamping the bearing sleeve 32 in adjusted position a clamp bolt 37 may be passed through an elongated slot 38 of the shank 31 into the extension 29. For turning the mounting stud 33 to adjust the grooving knife angularly the bearing sleeve 32 may be

slotted as seen at 39 and a clamp bolt 40 passed through projecting ears 41 thereof to spring said sleeve to the requisite extent for clamping securely the stud 33. The stud 33 has fixed at its inner end the grooving knife 42 which has its main portion extending diagonally at some little angle to the vertical and its lower end bent to constitute a U-shaped grooving edge 43 extending down into the guide passage 19. It will thus be observed that, by reason of the oblique mounting of the knife 42 as it extends downward from the stud 33, as said stud is turned on its axis, the operative edge 43 of said knife may be projected more or less as required into the guide passage 19 to produce a groove of the desired depth. It will further be noted that by a small angular adjustment of this kind, the wearing away of the knife as it is ground can be compensated for, and the cutting edge 43 held securely and rigidly at a uniform or a desired distance at all times from the bottom of the guide passage 19, thus insuring the production of a groove, the bottom of which is always a precisely uniform thickness from the bottom or other side of the welt. Suitable means may be provided for diverting the shaving produced by the grooving knife. For this purpose I show an angularly mounted guide plate or member 44 adjustably clamped to the base by a clamp bolt 45 passing through an elongated slot 46 in a horizontally extending portion of said member whereby said guide member may be adjusted with reference to the path of movement of the welt strip as required.

It may now be understood that the guide way or passage 19 for the welt strip may be set in adjusted position lengthwise of the face of the feed wheel 3 as required by the adjustment of the shank 16 as described in its slide way in the top of the upright 2. Also that the block 22 may be adjustably set in its slide way in the top of the upright 21 with reference to the block 15 so that it presents the guide face 22^a correctly positioned with reference to the guide passage 19 according to the width of the welt strip so that it is correctly and accurately guided sideways. Also that the bevel knife 25 mounted as described in the outer portion of the block 22 is held rigidly and securely, though with a capability of easy adjustment, so as to make a perfectly uniform bevel in the welt, to the extent desired. Also that the grooving knife 42 may be readily positioned by angular adjustment of the stud 33 so as to cause its cutting edge 43 to project into the welt passage 19 to the required extent for producing the desired depth of groove; such depth of groove being always uniform with reference to the other side of the welt to determine a uniform sewing thickness, since of course the other side or back of the welt is

reliably and uniformly supported by the block 15 forming the bottom surface of the guide passage 19. It will also be understood that the location of the groove widthwise of the welt may be readily varied if desired by loosening the clamp bolt 40 and adjusting the stud 33 endwise in the clamp sleeve 32. It will also be noted that the feed wheel 3 may be quickly adjusted vertically to properly coöperate with different thicknesses of 5
welt by merely turning the turn buckle 8 to the required extent. Thus all operative parts of the described mechanism are rigidly and securely mounted and held without the 10
use of any springs or other resilient elements in the machine, that would tend to cause uncertainty and unevenness in operation. I am aware that the invention in its various features may be embodied in other specific forms 15
without departing from the spirit or essential attributes thereof, and I therefore desire the present embodiment to be considered as 20
illustrative and not restrictive, reference being had to the appended claims rather than 25
to the foregoing description to indicate the scope of the invention.

Having described my invention, what I claim as new and desire to secure by Letters Patent is:

30 1. A machine of the kind described, comprising a guide way for a welt strip, feeding means mounted in operative relation thereto and equipped with provision for adjustment to engage different thicknesses of welts. 35
means for positively and definitely adjusting said guide way transversely of the direction of feed, and a grooving cutter fixedly mounted for positive adjustment and extending into said guide way to act on a welt passing therethrough.

2. A machine of the kind described, comprising an inclosed guide way for a welt strip, a grooving knife fixedly mounted in operative relation thereto, a feed wheel

mounted to engage a welt in said guide way, 45 and means for positively adjusting said wheel to position it for different thicknesses of welts.

3. A machine of the kind described, comprising an inclosed guide way for a welt strip having one portion thereof constituting the bottom and one side thereof, and another portion constituting an opposite side thereof, said second portion of said guide way mounted and equipped for positive adjustment transverse of the direction of welt feed and having a beveling knife fixed thereto.

4. A machine of the kind described, comprising a guide way for a welt strip composed of two parts, one thereof constituting a base and one side wall, and the other thereof constituting another side wall and mounted and equipped for adjustment relative to the first part and having a cutter fixed therein.

5. A machine of the kind described, comprising a base, a guide way formed in two transverse parts and each adjustable on said base, one of said parts constituting the bottom, one side wall and top of such guide way and the other part constituting the other side wall thereof and equipped with a beveling knife, and feeding means coöperatively mounted with respect to such guide way for 70 advancing the welt strip therethrough.

6. A machine of the kind described, comprising a block formed with a recess to constitute the bottom and one side of a guide way for a welt strip, feeding means associated therewith, and a support bearing a beveling knife mounted for adjustment with reference to said recess and constituting a welt guide at the other side thereof.

In testimony whereof I have signed my 85 name to this specification.

JAY A. MACKEY.
